UNITED STATES PATENT OFFICE.

IRVEN FRANCIS DAINS, OF MONMOUTH, ILLINOIS, ASSIGNOR TO WESTERN STONE-WARE COMPANY, A CORPORATION OF ILLINOIS.

LOADING DEVICE.

Application filed October 25, 1926. Serial No. 143,859.

This invention relates to loading devices and more particularly to car loading implements, although it may be employed with equal advantage for other purposes.

5 It contemplates more especially the provision of means whereby fragile articles may be efficiently packed in large quantities for shipment without subjecting them to destructive impacts imparted thereto consequent to the travel or movement of the conveyance.

The tremendous breakage incident to the shipping of fragile articles such as earthenware jars, has necessitated the adaptation 15 of shock absorbing expedients commonly termed fillers which although effective, nevertheless have not proven entirely satisfactory with known methods of packing.

It has been found desirable to pack fragile articles very compactly to prevent relative movement therebetween. Thus, the vibratory impulses imparted to the container or conveyance will not be transmitted to the articles individually, but collectively, there- 25 by in a measure vibrating the articles in unison with the conveyance without damage to either.

One object of the present invention is to provide means whereby fragile or other articles may be arranged in a container or conveyance with the compactness necessary to eliminate or at least reduce breakage to a minimum.

Another object is the provision of a portable appliance of simple construction, capable of imparting appreciable movement to packed articles for effecting the desired compactness thereof.

A further object is the provision of an inexpensive, durable packing implement, which is adjustable to enable the ready association and disassociation thereof with the interior of a conveyance for loading purposes.

45 Other objects and advantages will appear from the following description of an illustrated embodiment of the present invention.

In the drawings:

Figure 1 is a sectional view in elevation 50 showing a conveyance wherein an appliance embodying features of the present invention is disclosed.

Figure 2 is a sectional view taken substantially along line II-II of Figure 1.

Figure 3 is a sectional view taken substantially along line III-III of Figure 1.

Figure 4 is a view in elevation of the movable member co-operable with the means disclosed in Figure 3.

Figure 5 is a sectional view taken substantially along line V-V of Figure 2.

The structure selected for illustration is shown applied to a conveyance, in this instance a freight car 10 of standard construction wherein an appreciable number of fragile articles such as earthen jars 11 are carefully packed in superposed relation with a suitable filler such as prairie hay 12 interposed between the individual jars to prevent direct contact therebetween, the filler serving to provide a shock absorbing medium.

It is important to note that the shocks and vibrations imparted to the articles 11 incident to the travel of the conveyance 10, will cause movement between the articles which results in their destruction with appreciable damage. To eliminate or at least reduce the possible movement between the articles 11 to a negligible factor, it has been found essential or at least highly desirable to compactly arrange the articles 11 by increasing the confinement thereof; thus preventing movement therebetween and eliminating the damage thereto consequent of such movement.

In the present embodiment, the means for increasing the confinement of the articles 11 within the conveyance 10 after they are suitably arranged therein, comprises a standard 13, in this instance a vertically disposed I-beam, it being maintained in such position by a floor bracket 14 of common construction rigidly secured to an extremity of the I-beam 13 in any appropriate manner. The fact that the standard 13 constitutes the stationary member of the means herein employed for the purpose set forth, it is desirable to provide stabilizers therefor at a point removed from the floor of the conveyance. The stabilizers, in the present embodiment, consist of extensible members 15, in this instance two, pivotally associated with the standard 13 as at 16 to provide divergent arms adapted to abut against a portion of the conveyance 10. The members 15 consist of a tubular shell 17 which telescopically receives a rod 18 provided with a plurality of apertures 19 along the length thereof.

to receive an appropriate pin 20 for limiting the inward movement of the rods 19 which obviously may be hollow or solid as commercial practice may dictate. The telescopic rod 18 terminates in a bent extremity 21 engageable with a vertical surface, in this instance with a ceiling beam 22 of the conveyance 10, whereby the spaced extensible members 15 serve to stabilize the standard 13 in order to rigidly maintain the latter in a vertical position, and to render it selectively detachable with convenience.

The quantity of articles packed within the conveyance depends largely on the size of the shipment; however, it is possible to pack the conveyance, such as a freight car, commencing with the ends thereof, to the extent of the doors whereupon a partition 23 is provided to confine the articles 11. Disposed adjacent the partition 23 is a wheeled movable frame 24 supported on suitable castors 25 for a purpose which will herein-after be apparent. The standard 13 being preferably spaced from the partition 23, has associated therewith means, in this instance, a screw-jack 26 of standard construction which has a bracket 27 removably secured to an end thereof to slidably engage the standard 13 whereby the screw-jack 26 may be maintained thereon in any selected position, the other end of the screw-jack 26 impinging against the movable frame 24 which is preferably provided with socket plates 28 to receive the extensible portion 29 of the screw jack 26. As shown, the bracket 27 consists of a pair of spaced plates 30 and 31, having carriage bolts 32 interposed therebetween to receive the standard 13 therein, it being understood that the screw jack 26 is secured to the plate 30 in any appropriate manner.

With the arrangement of parts thus far described, it will be apparent that manipulation of the screw jack 26 in the ordinary manner will cause the member 29 thereof to move outwardly in engagement with the movable frame 24 to impart movement to the partition 23 whereby the confinement of the articles 11 is increased to such a degree of compactness as to prevent movement between the articles, thereby preventing breakage or damage thereto caused by vibration incident to the travel of the vehicle.

When the partition 23 has been moved to its desired position, the bottom thereof may be secured against movement by means of nails or other fasteners whereupon the jack 26 may be slidably raised to another position to effect corresponding movement of the upper portion of the partition 23 so that it may assume a vertical position.

Another screw jack 33 is preferably disposed above and in spaced relation with the screw-jack 26, the former being pivotally

associated with the standard 13 by means of an appropriate joint 34 which is secured in any appropriate manner to the standard 13, the screw jack 33 being pivotally movable upwardly to inoperative position when its use is not desired; thus any number of screw-jacks may be employed to accomplish the desired end, the number depending upon the particular conditions to which the device hereinabove described is applied. Obviously, any other suitable mechanism may be substituted for the screw-jacks for effecting movement of the movable member to increase the confinement of the articles arranged within the container or conveyance.

It will be apparent from the above description, that a novel portable device has been provided to compactly arrange an appreciable number of articles within a container to eliminate or at least decrease the breakage thereof to a minimum.

I am aware that many changes may be made, and numerous details of the construction may be varied through a wide range without departing from the principles of this invention, and I therefore do not purpose limiting the patent granted hereon, otherwise than necessitated by the prior art.

I claim as my invention:

1. The combination with a container adapted to receive articles therein, of means for compactly arranging said articles, said means including a movable member for confining said articles within a portion of said container, a vertically disposed stationary member fixable to said container, and means slidable on said stationary member for urging said movable member against said articles.

2. The combination with a container adapted to receive articles therein, of means for compactly arranging said articles, said means including a movable member for confining said articles within a portion of said container, a vertically disposed stationary member fixable to said container, and means slidable on said stationary member for urging said movable member against said articles, said slidable means comprising a screw-jack adjustable for concentration on selective portions of said movable member.

3. The combination with a container adapted to receive articles therein, of means for compactly arranging said articles, said means including a movable member for confining said articles within a portion of said container, a vertically disposed stationary member fixable to said container, and means slidable on said stationary member for urging said movable member against said articles, said slidable means comprising a screw-jack adjustable for concentration on selective portions of said movable member, and another jack pivotally associated with stationary member, said pivotally associated

jack being shiftable to a position parallel to said other jack.

4. The combination with a conveyance adapted to receive articles therein, of means for compactly arranging said articles, said means including a wheeled movable member adapted to confine said articles in a portion of said conveyance, a vertically disposed column fixable to said conveyance, said column having a floor supporting bracket therein, extensible diverging members pivotally secured to said column to engage the conveyance at spaced points to maintain said column in fixed position, and means associated with said column to cause said movable member to increase the confinement of said articles.

5. In a device of the character described, a wheeled movable member, a vertical column having a floor supporting bracket thereon, extensible stabilizing members associated with said column, and means for varying the spaced relation between said movable member and column.

25 6. In a device of the character described, a wheeled movable member, a vertical column having a floor supporting bracket thereon, extensible stabilizing members associated with said column, means for varying the spaced relation between said movable member and column, and means auxiliary to and spaced from said urging means.

7. In a device of the character described, a wheeled movable member, a vertical column having a floor supporting bracket thereon, extensible stabilizing members associated with said column, means for varying the spaced relation between said mov-

able members and column, and means auxiliary to and spaced from said urging means, 40 said urging and auxiliary means comprising individually operable screw-jacks.

8. In a device of the character described, a wheeled movable member, a vertically disposed stationary member, means for stabilizing said stationary member in its operative position, and means slidably and removably mounted on said stationary member for actuating said movable member.

9. The combination with a container 50 adapted to receive articles therein, of a loading device for compactly arranging said articles comprising a stationary member, a movable member, and means interposed between said members for actuating said movable member, said stationary member and said means being adapted to be entirely removed from said container when said articles are compactly arranged.

10. The combination with a car adapted 60 to receive articles therein, of means for compactly arranging said articles comprising an end wall for said articles, a shiftable compacting device for engaging said wall, an abutment removably anchored to said car, 65 and means between said abutment and shiftable device for shifting the latter for compacting said articles, said last named means holding said device in shifted position for securement of said wall, said device abutment and means being removable after the 70 securement of said wall.

In testimony whereof I have hereunto subscribed my name.

IRVEN FRANCIS DAINS.
